UNITED STATES PATENT OFFICE

WILLIAM J. STAPLETON, OF MINNEAPOLIS, MINNESOTA

FLOATABLE RECORD-INSTRUMENT LOCK

Application filed January 21, 1929. Serial No. 333,977.

My invention provides an efficient device whereby the various instruments used on vessels to indicate time, speed, direction, location, list of ship, and the like, may be secured as a permanent record in case of accident which threatens to or does result in the sinking or abandonment of the vessel, and generally stated, the invention consists of the novel devices, combinations of devices and arrangement of parts herein-after described and defined in the claims.

It is a known fact that vessels frequently are lost at sea under conditions where, for the purpose of insurance and the ship-owner's liability for the loss of life or property, it is of utmost importance that proof be produced as to all of the important conditions or facts relating to the accident. It is customary for vessels to carry a chronometer or clock, a compass, a speed indicator, a longitude and latitude indicator, and also an instrument which will indicate, in degrees, the list or lateral tilt of the vessel.

The invention may be carried out in various different ways and I have in the accompanying drawings, illustrated one scheme for accomplishing the same.

Referring to the drawings wherein like characters indicate like parts throughout the several views.

Fig. 1 is a plan view of the complete instrument with the cover thereof opened up;

Fig. 2 is a section taken on the line 2—2 of Fig. 1;

Fig. 3 is a section taken on the same line as Fig. 2 but showing the cover of the casing closed;

Fig. 4 is a section taken approximately on the line 4—4 of Fig. 1, but showing the cover of the casing closed; and

Fig. 5 is a fragmentary section taken on the line 5—5 of Fig. 4.

The numeral 6 indicates a floatable casing of rectangular form made of wood or other material and having such wood displacing capacity that it will float with all of the instruments therein applied. This casing is provided with a normally open cover 7 connected thereto by a hinge 8. This cover,

when closed, will form a water-tight joint with the casing and for that purpose packed joints, not shown, may be employed. To lock the cover closed, it is shown as provided with a hasp 9 for co-operation with a staple 10 on the casing and through which staple a padlock 11 may be applied to lock the cover closed. This cover, however, as will hereinafter appear, will be closed only in case of an accident that results in ultimate abandonment of the vessel.

Just below its uppermost portion, the casing 6 is provided with an instrument board 12 that carries a plurality of instruments such as a chronometer or clock 13, a compass 14, a speed indicator 15, a longitude and latitude indicator 16, and a list instrument 17, which latter at all times indicates, in degrees, the list or lateral tilt of the vessel. The faces of these instruments are all exposed above the instrument board, but their bottoms depend through the board, and, for the purposes of this case, it may be assumed that the said bottoms of the several instruments are flexible or compressible so that when pressed upward, the movable parts of the respective instruments will be stopped and held in the exact positions that they occupy at the time of depression which is produced by a lock mechanism presently to be described.

The numeral 18 indicates a rectangular frame mounted for vertical movements by means of depending rods 19 that work through guide brackets 20 secured on the bottom of the casing. In the particular arrangement illustrated, this frame 18 has three lock bars 18^a, 18^b, and 18^c. When the frame 18 is raised to its limit, lock bar 18^a will press the bottoms of the instruments 16 and 17 upward and lock said instruments; the lock bar 18^b will press upward the bottom of instrument 15 and lock the same; and the lock bar 18^c will press upward the bottoms of instruments 13 and 14 and lock said last two noted instruments.

The cover or lid 7 will be closed only in case of an accident such as above indicated, but means is provided whereby closing of this cover or lid will raise the frame 18 and

lock the several instruments as above stated. To accomplish the locking action just noted, parallel levers 21 are intermediately pivoted to bearing brackets 22 on the bottom of the casing 6. The free ends of the long arms 5 of the levers 21 engage lugs 23 on the central portions of the side bars of the frame 18 while the short ends of said levers 21 are, by slot and pin connections 24, connected to the lower ends of a pair of depressible plungers 25 that are mounted to slide vertically through the instrument board 12 and through guides 26 on the inner side of the casing 6. Normally the frame 18 will be in 10 its lower portion and the upper ends of the plungers 25 will project above the top of the casing as shown in Fig. 2, but when the cover 7 is closed it will depress plungers 25 and raise the frame 18 causing all of the instruments to be locked in a manner previously described.

To provide means for positively securing and locking the lock frame 18 in its raised instrument-locking position even after the 25 cover 7 has been opened, there is provided a self-acting pawl and ratchet device comprising a ratchet wheel 27 and a spring-pressed lock pawl 28. The ratchet wheel 27 is secured on a short shaft 29 journaled in bearing brackets 30 on the bottom of the casing and the pawl 28 is pivoted to a projection of the bracket 30. Shaft 29 also carries a spur gear 31 that meshes with a vertical movable rack bar 32 arranged to slide in a guide 33 secured on the bottom of the casing; the upper end of the rack 32 being attached to the central portion of the lock bar 18^b so that when frame 18 is raised, shaft 29 will be rotated and the pawl and ratchet device will 40 lock frame 18 in its raised operative or instrument-locking position independently of the cover 7.

The casing 6 may be normally set on the deck 34 or other suitable support and normally will be locked to said support by suitable means such as a pair of spring pressed latches 35 mounted on the deck or support 34 and normally engageable with lugs 36 on the sides of the casing 6. The casing may be 50 locked to the deck or support 34 as long as the cover 7 is in an open position or, in other words, has not been closed for the purpose of locking the several instruments. The cover 7 is shown as provided with a pair of latch-releasing arms 37 which, when the cover is 55 closed upon the casing, will engage the beveled upper ends of the latches 35 and force the same into releasing positions, as shown in Fig. 4. To lock the latches 37 in the releasing positions so that they will not re-engage with the lugs 36 before the floating casing has had a chance to float clear of the deck or support 34, I have shown dogs 38 65 pivoted to the deck or support 34 and en-

gageable with lugs on the dogs 38 when the latter are retracted, as shown in Fig. 4.

From the foregoing it will be seen that locking of the several instruments and releasing of the floating casing containing the instruments is performed by the single operation, to wit: the closing of the cover of the casing, and that this closing of the cover of the casing will take place only after an accident has occurred and the vessel is about 70 to be abandoned. When the casing is closed and released from the deck or support, it will be free to float away if the vessel should sink. If the instrument is not normally carried where it will be free to float away, the 75 person who closes the casing may, of course, throw the casing with its instruments overboard or place the same where it will be free to float when the vessel does sink. A floating object such as the casting with its closed instruments and the records therein contained, will be quite certainly picked up 80 sooner or later and will then afford positive evidence as to all important conditions that existed at the time of the sinking of the vessel. Obviously the device may be found useful in connection with aeroplanes, dirigibles, and the like.

What I claim is:

1. In a device of the kind described, a 95 floatable casing having a displaceable cover, a plurality of indicating instruments applied in said casing, normally inactive locking means operative to lock all of said indicating instruments to show conditions existing at the time of locking and means whereby closing of the cover of said casing will render said lock operative.

2. A device of the kind described comprising a floatable casing, a plurality of indicating instruments applied to said casing, means operative at will to lock the several instruments and thereby retain the record of the conditions existing at the time of locking, means normally locking said casing to a relatively fixed support, and means whereby said casing will be released from 100 said support when the said instruments are locked.

3. The structure defined in claim 2 in further combination with a support for said casing, latches on said support and engageable with said casing to secure the same when the cover of said casing is open, and devices carried by the cover of said casing 110 operative on said latches to retract the same and release the casing from said support when said cover is closed and the instruments in said casing are locked.

4. A device of the kind described comprising a floatable casing, a plurality of independently-driven timed recording instruments applied to said casing, means operative at will to lock the several independently-driven instruments against further move- 115 120 125 130

ment to thereby retain records of the conditions existing at the time of locking thereof, and means for releasing said casing and permitting the same to float away from a vessel by which it is carried.

5. A device of the kind described comprising a floatable casing, a plurality of indicating instruments applied to said casing, and means operative at will to lock the several instruments and thereby retain the record of the conditions existing at the time of locking, in further combination with a support for said casing, latches on said support engageable with said casing to normally retain the same in position, and means operative on said latches to release said casing from said support when the instruments therein contained are locked.

10 In testimony whereof I affix my signature:
15 WILLIAM J. STAPLETON.
